UNITED STATES PATENT OFFICE

2,603,349

PACKAGING STRIP

Martin Van Antwerpen, Milwaukee, Wis.

Application June 17, 1949, Serial No. 99,670

2 Claims. (Cl. 206—62)

1

This invention appertains to packing and shipping of fragile articles, such as automobile window glass.

One of the primary objects of the invention is to provide a cushioning and shock absorbing packaging strip for engaging and supporting the edges of a group of glass plates or sheets in a shipping carton, whereby the sheets will be effectively held and protected against breakage.

Another salient object of the invention is to provide a packaging strip which merely includes an outer carrying or base strip formed from flat material, such as fiber board, and an inner strip preferably formed from double corrugated board, secured to the base strip and having U-shaped, outwardly projecting spaced portions provided with notches for receiving the glass to prevent lateral shifting thereof, the material from said notches being bent in overlapping relation toward the base strip to form cushioning seats for the edges of the glass.

A further object of the invention is to provide cushioning pads of corrugated board or the like under the folded in portions to provide additional shock absorbing members for supporting the glass.

Another further object of the invention is to provide a cushioning strip of such a character, that the same can be readily folded and bent around the corners of cartons to effectively protect the corner edges of sheets of glass.

A still further object of the invention is to provide a packaging and cushioning strip of the above character which can be placed upon the market and fabricated at a small cost.

With these and other objects in view the invention consists in the novel construction, arrangement and formation of parts, as will be herein-after more specifically described and claimed and illustrated in the accompanying drawing, in which drawing,

Figure 1 is a side elevational view showing the packaging and cushioning strips in use for holding a group of sheets of glass in a carton, the carton being shown in section.

Figure 2 is a top plan view of one of the packaging and cushioning strips.

Figure 3 is a top plan view of the blank of the corrugated board before the folding and gluing thereof to the base strip.

Figure 4 is an enlarged transverse sectional view through the packaging strip taken on the line 4—4 of Figure 2, looking in the direction of the arrows, the sheets of glass being shown in dotted lines.

Figure 5 is an enlarged transverse sectional

2

view through a packaging strip taken on the line 5—5 of Figure 2, looking in the direction of the arrows, showing the glass in dotted lines.

Referring to the drawing in detail, wherein similar reference characters designate corresponding parts throughout the several views, the letter S generally indicates the packaging and cushioning strips for holding a group of glass plates G in a shipping carton C.

10 The carton C forms no part of the present invention and can be considered as of a type now generally found on the open market for shipping flat articles. As shown, however, the carton C includes longitudinally extending side walls 6 and end walls 7.

15 The cushioning strip S can be in a continuous length for extending entirely around the periphery of the glass plates G and between the glass plates and the side and end walls of the carton, or of a series of short lengths as illustrated in the drawing. Each strip S includes a base 8 formed from a flat length of material such as fiber board, and an inner length of material 9, preferably formed from double corrugated board. The 20 double corrugated board can be of the type including inner, outer and intermediate facing sheets 10, and corrugated liner sheets 11, between the inner and outer and intermediate facing sheets 10. The inner corrugated board 9, is secured at spaced points to the base strip in any preferred way, such as by the use of an adhesive. In the formation of the cushioning and packaging strip S, the corrugated board 9 is of a greater 25 length than the base 8, due to the fact that the corrugated board 9 is folded into a certain novel form, before its attachment to the base 8 by the adhesive.

30 In forming the inner corrugated board 9 for the fabrication of the strip S, the same is weakened along intermediate parallel lines 12 on opposite sides of the transverse center thereof and by parallel weakening lines 13 adjacent to the opposite ends thereof. Between the weakening lines 12 and 13, the inner corrugated board 9 is slotted by parallel slots 14, which terminate short of the weakening lines 12 and 13. The material 35 between the slots 14 is slotted transversely, as at 15, at a point intermediate the ends of the parallel slots 14 to provide tongues 16.

The strip is also preferably weakened by score lines 17 on its under face. These score lines 17 extend transversely of the inner corrugated board 8 and are arranged in spaced parallel relation and between the score lines 12 and 13 on opposite sides of the transverse slot 15.

As is clearly shown in Figure 5, the corrugated board 9 is bent, by suitable machine, to provide outwardly projecting substantially U-shaped projections 18 on the score lines 12, 13 and 17. The inner face of the corrugated board 9 between the U-shape projections 18 and beyond the U-shaped projections are the portions of the corrugated board 9 which are united to the base 8 by the suitable means, such as an adhesive.

The tongues 16 are folded inwardly one upon the top of the other, within the U-shaped projections 18, as is clearly shown in Figure 5.

The formed strips S are placed around the edges of the group of glass plates G, as is clearly shown in Figure 1 and the edges of the glass fit within notches 19, defined by the folding in of the tongues 16. This prevents lateral shifting of the glass plates relative to the cushioning strips and the edges of the glass sit against the folded in tongues which form a cushioning support therefor. If desired, cushioning pads 20 can be placed between the base 8 and the tongues 16 to form an additional support for the glass plates. As is clearly shown in Figure 1, the cushioning strips fit between the walls of the carton and effectively brace the carton and hold the glass plates centrally within the carton. The strips can be easily bent around the corners of the carton on the score lines 12, and there will be a U-shaped projection on each side of the corner of the groups of sheets of glass.

From the foregoing description, it can be seen that I have provided a simple cushioning and packaging strip for sheets of glass which can be economically fabricated.

Changes in details may be made without departing from the spirit or the scope of the invention, but what I claim as new is:

1. A packaging and cushioning strip comprising a base ply of sheet material, an inner ply of corrugated board secured to the base ply at

spaced points having inwardly projecting substantially U-shaped portions between the points of securement of the inner ply to the base ply, said U-shaped portions being provided with longitudinally extending notches for receiving the edges of the material to be protected, tongues joined with the inner ply arranged in over-lapping relation and disposed in the U-shaped portions at the bases of the notches defining seats, and cushioning pads of corrugated board arranged in said U-shaped portions between the base ply and said tongues.

2. A packaging and cushioning strip adapted to be placed about the edge of a sheet of plate glass comprising a longitudinally extending base ply and a longitudinally extending inner ply secured to the base ply at spaced points having inwardly projecting substantially U-shaped portions between the points of securement of the inner ply to the base ply, said U-shaped portions being arranged in longitudinal alignment and being provided with longitudinally extending notches, said notches being also in longitudinal alignment for receiving the glass to be protected, and tongues joined with the inner ply arranged in over-lapping relation and disposed in the U-shaped portions at the bases of the notches defining cushion seats for the marginal edge of the glass.
